His Attorney.

UNITED STATES PATENT OFFICE

2,457,521

ELECTRIC-LIGHT FIXTURE

George B. Benander, Oaklawn, R. I., assignor, by
mesne assignments, to Monowatt Incorporated,
Providence, R. I., a corporation of Connecticut

Application January 3, 1946, Serial No. 638,776

7 Claims. (Cl. 173—358)

1

The present invention relates to electric light fixtures of the type termed usually "pin-up" lamps, this being an electric light fixture adapted to be hung on a wall and having a length of cord with a plug at its end for connection with an electric wall receptacle.

The object of my invention is to provide an improved "pin-up" lamp and an improved lamp socket adapted for use in a pin-up lamp, which is unusually simple in structure and capable of being manufactured at low cost; and for a consideration of what I believe to be novel and my invention; attention is directed to the following specification and to the claims appended thereto.

In the drawing, Fig. 1 is a side elevation, partly in section, of a "pin-up" lamp embodying my invention; Fig. 2 is a sectional view taken on line 2—2, Fig. 1, and Fig. 3 is an exploded perspective view of parts of the fixture.

The fixture comprises a lamp socket 1, a bracket 2 and a wall plate 3.

The lamp socket comprises a casing formed in two parts 4 and 5 which may be made of a suitable molding compound. The two parts are fastened together by a transversely extending hollow rivet 6 located in an opening 7 which extends through the two parts of the casing. Inside the casing are transversely extending walls 8 and 9 formed integral with the casing parts 4 and 5 to define a lamp contact or screw shell housing 10 located above wall 8, and a wiring space 11 located between walls 8 and 9. In the portion of the wiring space 11 in casing part 5 is a wiring shelf or table 12; also in such portion is a passage 13 located at about the center of shelf or table 12 through which extends the end of an electric cord 14. In walls 8 and 9 and shelf 12 are rectangular passages 14a. Passages 14a are partly in casing part 4 and partly in casing part 5 so that in each part they are in the form of notches as shown clearly in Fig. 3.

Viewed from another aspect, the walls 8 and 9 and shelf 12 in casing part 5 form a transverse partition in the top surface of which is a transversely extending wiring recess across which extend two spaced slots and at the center of which is a passage for an electric cord. The portion of the wiring recess 11 in casing part 4 has no function other than that of decreasing the amount of material required.

In housing 10 are lamp contacts which as shown comprise a screw shell 15 of suitable metal and a center contact 16 of similar metal. Formed integral with shell 15 and center contact 16 respectively are extensions 17 and 18 which fit

2

edgewise in passages 14a. Extensions 17 and 18 have inturned ends 19 and 20 which fit under wall 9 to hold the shell and center contact from axial movement. In housing 10 are projections 21 which fit into two openings 22 in shell 15 to hold the shell from turning. The end of the electric cord is brought in through passage 13, one conductor extends each way, and the bared ends of the conductors are positioned in passages 14a in the casing part 5 beneath and around the extensions 17 and 18. The portions of passages 14a which are in the table 11 may be slightly wider than the portions in walls 8 and 9 to accommodate the conductor ends.

In assembling the socket, the casing part 5 may be positioned in a suitable fixture, the electric cord end passed through opening 13 and the ends of the two conductors of the cord bent sideways in opposite directions across the shelf to position the bared conductor ends across the slots in the shelf. The screw shell 15 and center contact 16 are then positioned in casing part 5, the extensions 17 and 18 being forced down into the slots and carrying the bared conductor ends with them so that the conductor ends are fixed under the extensions. The casing part 4 is then placed on casing part 5 and the two parts are fastened together by the rivet 6. There is thus provided a unitary wired socket.

It will be noted that the structural parts are all assembled in the one casing part 5, which may be termed the base part, and that the casing part 4 functions as a cover part. This arrangement is of substantial advantage from an assembly standpoint in that it enables the lamp socket to be assembled on the end of the cord at low cost and with simple fixtures. The shelf 12 in the base part performs an important function in that it supports the wire ends during assembly and insures that they are properly positioned.

It will be seen that the socket comprises only five parts, the two casing parts 4 and 5, the two contact parts 15 and 16 and the rivet 6. There are no binding screws, fastening screws or bolts. And, as will be clear from the foregoing, the structure can be assembled with the cord attached very quickly and easily and by the use of a simple assembling fixture. It will be noted from Figs. 2 and 3 that the two conductor ends of the electric cord have a right angle bend across the shelf at the inner end of passage 13. This right angle bend in the conductor ends serves to provide a strain relief for the cord, pull on the cord being taken around the corners and not on the connec-

tions of the bared conductor ends with the extensions 17 and 18.

The one end of bracket 2 is fastened to the socket by a bolt 23 which extends through the hollow rivet. In the present instance, the casing part 5 is provided with a flattened portion 24 at the point where passages 7 and 13 are located and bracket 2 has an angularly bent end 25 which fits against the flattened portion just below cord passage 13 and is held by bolt 23. The end of the bolt may thread directly into a tapped opening in end 25 or it may pass through an opening in such end and be held by a suitable nut and washer 26.

The other end of the bracket may be fastened to the wall plate in any suitable way such as by the bolt and nut 27. Bracket 2 is curved in cross section. The cord 14 may extend along and be housed by the bracket and be passed through holes 28 and 29 in wall plate 3. The end of the cord will be provided with a suitable wall plug (not shown). In the wall plate is an opening 30 for use in hanging the fixture on a wall.

By my invention, I provide a socket of simple construction which comprises a minimum number of parts and which is easily and quickly wired when the socket is assembled. The socket with the cord length thereon is easily attached to a bracket to form a "pin-up" lamp.

The way in which the cord enters the socket and is attached to the contacts therein is especially advantageous since by such arrangement I provide a construction in which the connections can be simply and easily made without binding screws and at the same time I provide a satisfactory strain relief for the cord whereby pull on the cord will not affect its connections with the contacts.

What I claim as new and desire to secure by Letters Patent of the United States is:

1. In combination, a lamp socket comprising a casing split longitudinally to provide a base part and a cover part, walls forming a wiring shelf in the base part having narrow spaced crosswise slots therein, said base part having a passage in its wall the inner end of which terminates between said slots at the center of said shelf, lamp contacts in the socket, a cord extending along said passage having its conductor ends bent at right angles in opposite directions along said shelf, strip metal contact members of a thickness equal substantially to the width of said slots positioned edgewise in said slots, the bared ends of said conductors being positioned in said slots beneath said contact members to make electrical contact therewith and attach the conductor ends to the socket, means connecting said contact members to said lamp contacts, and means fastening the cover part and base part together.

2. In combination, a lamp socket comprising a longitudinally split casing having an open end to receive a lamp end and a closed end, transverse walls in the casing spaced from said closed end defining a contact housing and a wiring recess, said walls having transversely spaced axially extending passages therethrough and said casing having an opening through its side wall in line with and communicating with said wiring recess between said passages, a pair of lamp contacts in said contact housing having extensions positioned in said passages, an electric cord which extends through said opening, has its two conductors extending in opposite directions transversely of said recess and its bared ends positioned in the passages and held under said extensions, and a hollow rivet which extends transversely through

said casing between said transverse walls and the lower end of the casing to hold the casing together whereby a bracket may be attached to the side of the socket by fastening means extending through said hollow rivet.

3. In combination, a lamp socket comprising a casing-split longitudinally to provide complementary casing parts, walls forming a wiring shelf in one of said parts having narrow spaced crosswise slots therein, walls defining a passage in the casing, the inner end of which terminates between said slots at the center of said shelf, lamp contacts in the socket, a cord end positioned in said passage having its conductor ends bent in opposite directions along said shelf, strip metal contact members of a thickness equal substantially to the width of said slots positioned edgewise in said slots, the bared ends of said conductor ends being positioned in said slots beneath said contact members to make electrical contact therewith and attach the conductor ends to the socket, means for connecting said contact members to said lamp contacts, and means for fastening the casing parts together.

4. In combination, a lamp socket comprising a casing split longitudinally to provide complementary casing parts, walls forming a wiring shelf in one of said parts having narrow spaced crosswise slots therein, walls defining a passage in the casing, the inner end of which terminates between said slots at the center of said shelf, lamp contacts in the socket, a cord end positioned in said passage having its conductor ends bent in opposite directions along said shelf, strip metal contact members of a thickness equal substantially to the width of said slots integral with said lamp contacts positioned edgewise in said slots, the bared ends of said conductor ends being positioned in said slots beneath said contact members to make electrical contact therewith and attach the conductor ends to the socket, said contact members and said casing housing having engaging parts to hold the contact members against axial movement, and means for fastening the casing parts together.

5. In combination, a lamp socket comprising a longitudinally split casing having an open end to receive a lamp end and a closed end, transverse walls in the casing spaced from said closed end defining a contact-housing and a wiring recess, said walls having transversely spaced axially extending passages therethrough and said casing having an opening through its side wall in line with and communicating with said wiring recess between said passages, a pair of lamp contacts in said contact housing having extensions positioned in said passages, an electric cord which extends through said opening, has its two conductors extending in opposite directions transversely of said recess and its bared ends positioned in the passages and held under said extensions, and means fastening the casing parts together.

6. In combination, a lamp socket comprising a casing split longitudinally to provide complementary casing parts, walls in one of said parts defining narrow spaced crosswise slots therein, walls defining a passage in said casing, the inner end of which terminates between said slots, lamp contacts in the socket, a cord end positioned in said passage having its conductor ends bent in opposite directions, strip metal contact members of a thickness equal substantially to the width of said slots, the bared ends of said conductors being positioned in said slots beneath said contact members to make electrical contact therewith

and attach the conductor ends to the socket, means for connecting said contact members to said lamp contacts, and means for fastening the casing parts together.

7. A lamp socket comprising a casing split longitudinally to provide complementary casing parts, walls forming a wiring shelf in one of said parts having narrow spaced crosswise slots therein, walls defining a passage in the casing, the inner end of which terminates between said slots at the center of said shelf, in which a cord end may be positioned with its conductor ends bent in opposite directions along the shelf, lamp contacts in the socket, strip metal contact members of a thickness equal substantially to the width of said slots positioned edgewise in said slots adapted to have the bared ends of conductor ends positioned beneath them to make electrical con-

tact therewith and attach the conductor ends to the socket, means for connecting said contact member to said lamp, and means for fastening the casing parts together.
